Primary Examiner — Sharon S Oum(74) Attorney, Agent, or Firm — McGarry Bair PC(57) CLAIM

The ornamental design for a ceiling fan assembly, as shown and described.

DESCRIPTION

FIG. 1 is a bottom perspective view of the ceiling fan assembly, showing my new design.

FIG. 2 is a top perspective view thereof;

FIG. 3 is a bottom view thereof;

FIG. 4 is a top view thereof;

FIG. 5 is a front view thereof;

FIG. 6 is a rear view thereof;

FIG. 7 is a right-side view thereof; and,

FIG. 8 is a left-side view thereof.
